UNITED STATES PATENT OFFICE.

IGNATIUS W. KAHN, OF DETROIT, MICHIGAN.

ALTERNATING-CURRENT-MOTOR STARTER.

1,232,322.

Specification of Letters Patent.

Patented July 3, 1917.

Application filed August 11, 1915. Serial No. 44,904.

To all whom it may concern:

Be it known that I, IGNATIUS W. KAHN, a citizen of the United States, residing at Detroit, in the county of Wayne and State of Michigan, have invented a new and useful Alternating - Current - Motor Starter, of which the following is a specification.

In the use of alternating current motor starters, as is common knowledge, the heaviest load comes on the line at starting and some provision must therefore be made for relieving the fuse whereby the maximum load capacity of the motor is determined. Various switches comprising a switch bar by which the running fuse is relieved of excess load, together with means for afterward automatically breaking the circuit through the switch bar to pass the entire current through the fuse under normal running conditions, are well known; and the present invention has reference to a switch of this nature that may be manufactured at an unusually small cost and which nevertheless possesses operative advantages over the more complex and expensive constructions.

The invention consists, in combination with a pivoted switch or running bar, of a fused alternating current circuit and means for actuating the bar, of a second pivoted switch or starting bar arranged to engage with a starting contact, and means for causing the starting bar to engage with the starting contact prior to the time the running bar closes the circuit through the running fuse whereby the fuse is relieved of excessive starting current. It also consists in means whereby the starting circuit is automatically broken upon the handle being released by the operator without at the same time breaking the normal running circuit; also in means whereby such a switch is adapted for use with current of more than single phase; and it further comprises the details of construction shown, described and claimed.

In the drawings, Figure 1 is a side view of a preferred embodiment of the invention, parts being broken away. Fig. 2 is a section on the line 2—2 of Fig. 1. Fig. 3 is a section on the line 3—3 of Fig. 1.

Supported upon an insulating slab or base 1 are the hinge switch jaws 2, the number of which varies with the number of phases,

and to these jaws current is brought through the conductors 3 from any desired source. The jaws support the pivots 4, upon each of which is mounted a running switch bar 5 arranged to be swung into engagement with a friction contact or running clip 6 of any desired form, and, when the circuit is completed as stated, current passes from the clip through the particular fuse 8, conductor 9 and line element 10 to the motor (not shown). Also mounted upon the slab at points opposite the corresponding clips 6 is a series of starting contact clips 12, from each of which a conductor 13 leads to the line element connected to the opposed running clip 6. The pivots 4 support the starting bars 14 whereby the circuits 2—12 may be closed, and the opposite ends 15 of the bars are connected to springs 16 which normally tend to hold the parts in about the position shown. Referring to each pair of switch bars, there is pivotally connected to the bar 14 at 18 a link 19, and projecting from the bar 5 at a point somewhat farther removed from the pivot 4 than the point 18, is a pin 21 which is received in a slot 22 formed in a second link 23. A spring 24, attached to the pin 21 and to a second pin 25 on the link 23, tends to hold the bar 5 in the position shown. The opposite ends of the links of each pair are pivotally connected to an arm 28 (preferably by a single pivot 29) and are insulated therefrom in any desired manner, such, for example, as indicated at 30 in Fig. 3. The several arms 28 are rigid with a shaft 31 supported in brackets 32, and may be actuated by a handle 33.

Operation.

The handle, being swung in clockwise direction (Fig. 1), swings the switch bars simultaneously about the pivots 4, but the starting bars 14, because of the relation of the points 18 and 21, make engagement with the contacts 12 before the running bars 5 reach the contacts 6. This prevents the excess of the starting current from passing through the fuses. As soon as the motor attains the desired speed, the operator releases the handle, whereupon the springs 16 throw the bars 14 counterclockwise about the pivots 4 and break the starting circuits, after which the current for the normal run-

ning load is taken only by the fuses 8 and conductors 9 to the line elements 10. This action is accompanied by a stretching of the relatively weak springs 24 and a slippage 5 of the slotted links 23 on the pins 21, the tension of these springs being insufficient to break the frictional engagement between the running bars and the contact clips 6. The position of the springs 16 is such that their 10 effectual leverage on the bars 14 is also exhausted before the friction between the bars 5 and contacts 6 is overcome; consequently the normal circuit is automatically maintained upon releasing the handle. Should it 15 now be desirable to break the circuit, it is only necessary to manually swing the handle counterclockwise, whereupon the pin 21 reaches the end of the slot, thus forming a rigid connection. As soon as the bars 5 leave 20 the contacts, they are quickly snapped away by the springs 24.

Thus it will be seen that there is involved a plurality of elements (2, 6 and 12) between which two circuits (2-6 and 2-12) 25 through which current may flow simultaneously, are to be completed and broken, together with means for completing and breaking said circuits comprising a plurality of switch bars (5, 14) and operating 30 mechanism (19, 23, 4 etc.) for imparting swinging movements to the bars and for causing one of the bars to complete one of the circuits (2-14-12) before the other bar completes the other circuit (2-5-6).

35 It is obvious that the details of construction may be changed considerably without departing from the spirit of the invention; for example, means other than the elements 28, 31-33 may be employed for actuating 40 the switch bars. And, while the circuits to the contacts 6-12 are shown divided at points spaced from the contact 12, it is clear that the divisions may actually take 45 place at the latter contacts, in which case one of the branches would be formed of the contact itself—in other words the wires 10 may be passed under the binding screws thus saving the metal of the conductors 13. I do not, therefore, wish to be limited otherwise than as indicated by the subjoined 50 claims.

I claim:—

1. A starting device for alternating current motors comprising a switch jaw, a pair 55 of opposed contacts, a pair of opposed switch bars pivotally mounted on the switch jaw, means for causing the switch bars to swing with reference to each other into engagement with the respective contacts and for 60 causing the bar for one contact to engage with the latter before the other bar engages with the other contact.

2. A starting device for alternating current motors comprising a base, a switch jaw 65 supported thereon, a pair of opposed con-

tacts also supported on the base, a pair of opposed switch bars pivotally mounted on the switch jaw, means for causing the switch bars to simultaneously swing in opposite directions into engagement with the respective contacts and for causing the bar for one contact to engage with the latter before the other bar engages with the other contact, and means for automatically removing one of the bars from engagement with the corresponding contact after both bars have been brought into engagement with the contacts. 70

3. A starting device for alternating current motors comprising a switch jaw, a pair 80 of opposed contacts, a running bar and a starting bar pivotally mounted in opposed relation to each other on the switch jaw, means for causing them to swing in opposite directions into engagement with the respective contacts, said last mentioned means including two links, each of which is pivotally connected to a corresponding bar, the distance from the pivotal axis of the starting bar to the point of its connection with 85 the corresponding link being less than the distance from the pivotal axis of the running bar to the point of its connection with its link, whereby the engagement of the starting bar with its contact is insured prior 90 to the engagement of the running bar with its contact. 95

4. A starting device for alternating current motors comprising a switch jaw, a pair 100 of opposed contacts, a running bar and a starting bar pivotally mounted in opposed relation to each other on the switch jaw, means for causing them to swing in opposite directions into engagement with the respective contacts, said last mentioned means 105 including two links each of which is pivotally connected to a corresponding bar, the distance from the pivotal axis of the starting bar to the point of its connection with the corresponding link being less than the 110 distance from the pivotal axis of the running bar to the point of its connection with its link, said last named connection being formed by a pin on the running bar and a slot in the link, resilient means tending to 115 hold the pin in such a position in the slot that the running bar is removed from its contact, whereby the engagement of the starting bar with its contact is insured prior 120 to the engagement of the running bar with its contact. 120

5. A starting device for alternating current motors comprising a switch jaw, a pair 125 of opposed contacts, a pivot carried by a switch jaw, a running switch bar and a starting switch bar mounted on the pivot, means for causing them to swing in opposite directions into engagement with the respective contacts, said last mentioned means including a pair of links and an arm to 130

- which they are pivotally connected, one of the links being joined to the running bar by a sliding connection, the other being pivoted to the starting bar at a distance from the pivot on the switch jaw less than the distance from said pivot to the sliding connection, and a spring tending to hold the running bar at one end of the sliding connection, whereby the starting bar is caused to engage with its contact prior to the engagement of the running bar with its contact.
6. A starting device for alternating current motors comprising a switch jaw, a pair of opposed contacts, a pivot carried by the switch jaw, a running switch bar and a starting switch bar mounted on the pivot, means for causing them to swing in opposite directions into engagement with the respective contacts, said last mentioned means including a pair of links and an arm to which they are pivotally connected, one of the links being joined to the running bar by a sliding connection, the other being pivoted to the starting bar at a distance from the pivot on the switch jaw less than the distance from said pivot to the sliding connection, a spring tending to hold the running bar at one end of the sliding connection, whereby the starting bar is caused to engage with its contact prior to the engagement of the running bar with its contact, and resilient means by which the starting bar is normally held out of engagement with its contact.
7. A starting device for alternating current motors comprising a switch jaw, a pair of opposed contacts, a starter bar and a running bar pivotally mounted on the switch jaw in opposed relation to each other, means for causing the bars to swing in opposite directions with reference to each other into engagement with the corresponding contacts and for causing the starter bar to engage its contact before the running bar engages its contact, and resilient means for normally holding the starting bar out of engagement with its contact.
8. A starting device for alternating current motors comprising a switch jaw, a pair of opposed contacts, a running bar and a starting bar pivotally mounted in opposed relation to each other on the switch jaw, means for causing them to swing in opposite directions into engagement with the respective contacts, said last mentioned means including two links each of which is pivotally connected to a corresponding switch bar, the distance from the pivotal axis of the starting bar to the point of its connection with the corresponding link being less than the distance from the pivotal axis of the running bar to the point of its connection with its link, whereby the engagement of the starting bar with its contact is insured prior to the engagement of the running bar with its contact, and resilient means for normally holding the starting bar out of engagement with its contact.
9. A starting device for alternating current motors comprising a switch jaw, a pair of opposed contacts, a pivot carried by a switch bar, a running switch bar and a starting switch bar mounted on the pivot, means for causing them to swing in opposite directions into engagement with the respective contacts, said last mentioned means including a pair of links and an arm to which they are pivotally connected, one of the links being joined to the running bar by a sliding connection, the other being pivoted to the starting bar at a distance from the pivot on the switch jaw less than the distance from said pivot to the sliding connection, a spring tending to hold the running bar at one end of the sliding connection, whereby the starting bar is caused to engage with its contact prior to the engagement of the running bar with its contact, and resilient means for normally holding the starting bar out of engagement with its contact.
10. A starting device for alternating current motors comprising a base, a plurality of switch jaws supported thereon, a plurality of pairs of opposed contacts, a plurality of pairs of opposed switch bars pivotally mounted on the switch jaws, one pair for each jaw, and means for simultaneously causing the members of the several pairs of switch bars to swing in opposite directions into engagement with the respective contacts and for causing the bars that lead to one set of the contacts to engage therewith before the bars that lead to the other set of said contacts engage with the latter.
11. A starting device for alternating current motors comprising a plurality of elements between which two circuits, through which current may flow simultaneously, are to be completed, means for completing said circuits comprising a plurality of switch bars and means for imparting swinging movements to the bars to cause one of the bars to complete one of the circuits before another bar completes another circuit.
12. A starting device for alternating current motors comprising a plurality of elements between which two circuits, through which current may flow simultaneously, are to be completed, means for completing said circuits comprising a plurality of opposed switch bars and means for imparting swinging movements to the bars in opposite directions to cause one of the bars to complete one of the circuits before another bar completes another circuit.
13. A starting device for alternating current motors comprising a switch jaw, a pair of opposed contacts, a running bar and a starting bar pivotally mounted in opposed

- relation to each other on the switch jaw, means for causing them to swing in opposite directions into engagement with the respective contacts, said last mentioned means including two links, each of which is pivotally connected to a corresponding bar, the distance from the pivotal axis of the starting bar to the point of its connection with the corresponding link being less than the distance from the pivotal axis of the running bar to the point of its connection with its link, whereby the engagement of the starting bar with its contact is insured prior to the engagement of the running bar with its contact, and means for automatically removing one of the bars from engagement with the corresponding contact after both bars have been brought into engagement with the contacts.
14. A starting device for alternating current motors comprising a plurality of elements between which two circuits, through which current may flow simultaneously, are to be completed and broken, means for completing and breaking said circuits comprising a plurality of switch bars and means movable by force applied in one direction for imparting swinging movements to the bars to cause one of the bars to complete one of the circuits before another bar completes another circuit, said last mentioned means also being movable thereafter by force applied in another direction for causing the bars to successively break the corresponding circuits.
15. A starting device for alternating current motors comprising a switch jaw, a pair of opposed contacts, a running bar and a starting bar pivotally mounted in opposed relation to each other on the switch jaw, means for causing them to swing in opposite directions into engagement with the respective contacts, said last mentioned means including two links each of which is pivotally connected to a corresponding bar, the distance from the pivotal axis of the starting bar to the point of its connection with the corresponding link being less than the distance from the pivotal axis of the running bar to the point of its connection with its link, said last named connection being formed by a pin on the running bar and a slot in the link, resilient means tending to hold the pin in such a position in the slot that the running bar is removed from its contact, whereby the engagement of the starting bar with its contact is insured prior to the engagement of the running bar with its contact, and means for automatically removing one of the bars from engagement with the corresponding contact after both bars have been brought into engagement with the contacts.
16. A starting device for alternating current motors comprising a plurality of ele-
- ments between which two circuits, through which current may flow simultaneously, are to be completed and broken, means for completing and breaking said circuits comprising a plurality of switch bars and means movable by force applied in one direction for swinging the bars to cause one of the bars to complete one of the circuits before another bar completes another circuit, said last mentioned means being movable by force applied in another direction to cause the bar whereby circuit is first made to break said circuit and to thereafter cause the bar whereby the circuit is last made to break said last made circuit.
17. A starting device for alternating current motors comprising a plurality of elements between which two circuits, through which current may flow simultaneously, are to be completed and broken, means for completing and breaking said circuits comprising a plurality of switch bars and means movable by force applied in one direction for swinging the bars to cause one of the bars to complete one of the circuits before another bar completes another circuit, said last mentioned means being movable by force applied in another direction to cause the bar whereby circuit is first made to break said circuit and to thereafter cause the bar whereby the circuit is last made to break said last made circuit, said bar swinging means including a resilient member whereby the breaking of said last made circuit is caused to take place rapidly.
18. A starting device for alternating current motors comprising a switch jaw, a pair of opposed contacts, a pivot carried by a switch jaw, a running switch bar and a starting switch bar mounted on the pivot, means for causing them to swing in opposite directions into engagement with the respective contacts, said last mentioned means including a pair of links and an arm to which they are pivotally connected, one of the links being joined to the running bar by a sliding connection, the other being pivoted to the starting bar at a distance from the pivot on the switch jaw less than the distance from said pivot to the sliding connection, and a spring tending to hold the running bar at one end of the sliding connection, whereby the starting bar is caused to engage with its contact prior to the engagement of the running bar with its contact, and means for automatically removing one of the bars from engagement with the corresponding contact after both bars have been brought into engagement with the contacts.
19. A starting device for alternating current motors comprising a pair of opposed contacts, pivot means located between the contacts, a running bar and a starting bar mounted on the pivot means, means for

causing the bars to swing in opposite directions into engagement with the respective contacts, said last mentioned means including a pair of links each of which is pivotally connected to a corresponding bar, the distance from the pivotal axis of the starting bar to the point of its connection with

the corresponding link being less than the distance from the pivotal axis of the running bar to the point of its connection with 10 the link.

In testimony whereof I sign this specification.

IGNATIUS W. KAHN.
